PRODUCTION OF ARTISTIC DESIGN USING
WICKING WET WITH A METALLIC SALT
SOLUTION THAT FORMS A COLOR ON EX-
POSURE TO LIGHT

Louis Jackson, New York, N. Y.

Application November 25, 1947, Serial No. 788,007

1 Claim. (Cl. 8—14)

1

This invention is concerned with the production of artistic designs, more particularly designs in color in relatively absorbent materials such as cloth, paper or the like. It is also directed to certain new and improved apparatus, particularly suitable for the production of designs in color, which apparatus is utilized in practicing my improved process.

My improved process permits the application of color to porous material such as paper, fabric, or similar materials, in such a way as to produce a multicolor design, the colors or dyes utilized becoming absorbed in the porous cloth or paper itself, as distinguished from the mere surface application of a color to these materials. In this way the color or dye stuff utilized to produce the colored effect actually enters into and forms a part of the fabric itself, or the porous paper, if paper is used, thus insuring a brilliance and permanency to the colored design that is not possible by the mere application of surface color to the material.

My invention is particularly suitable in producing colored designs on textile fabrics or on scarves. It is also useful in preparing wallpaper designs as well as for the preparation of colored designs of a more artistic nature, such as might be used for screens, lamp shades, or framed and hung on walls as wall decorations. It is possible, in accordance with my invention, to secure designs embodying any number of different colors, and by the use of certain coloring liquid, particularly the metal salts, it is possible to obtain a multitude of tints or variations in color, as well as shading effects which add considerably to the beauty of the design.

One of the outstanding advantages of my method of imparting colored decorations to porous or absorbent material is the fact that while successive designs which are extremely similar in pattern and color may be secured, no two of these designs are absolutely identical. While the designs are sufficiently similar in shading, tint, and configuration to allow them to fit into and blend in an overall design, such as for example on wall paper, the individual characteristics of each of the separate individual designs adds greatly to the artistic effect of the whole.

In carrying out my invention, I may utilize dyes of a wide variety, as well as solutions of metal salt, such as silver nitrate, or gold chloride, which permits obtaining a variety of intricate and very beautiful shading effects. The colors or dyes may be organic liquids such as ani-

2

line dyestuffs, or they may be inorganic colors. I have obtained very satisfactory effects with dyes or colors secured by extracting vegetable plants or fruits, such as the common berries, red cabbage, pokeberry berries, various flowers, or the like.

I have utilized with satisfactory results a number of chemicals, which may be utilized in water solution. Among such chemical solutions silver nitrate, silver chloride, tin chloride, mercuric chloride, lead nitrate, nickel nitrate or similar solutions.

My new and improved process for preparing artistic designs on absorbent material, such as textile fabrics, cloth, or paper, may best be illustrated in connection with the accompanying drawing, wherein:

Fig. 1 represents a perspective view showing how a square of absorbent material is placed over the slab on which are positioned the strips of porous cotton or other similar wick-like material, by which the colored solution is applied peripherally at the outer edges of the absorbent material on which the colored design is to be impressed;

Fig. 2 is a plan view of another form of supporting slab, to which the absorbent material on which the design is to be impressed may be applied exactly as shown in Fig. 1;

Fig. 3 shows a supporting slab of still another type;

Fig. 4 is a plan view of a fourth type of supporting slab, this type being provided with gutters which converge at a point approximately in the center of the slab;

Fig. 5 is a cross-sectional view of the supporting slab shown in Fig. 4, this view being taken along the line 5—5;

Fig. 6 is a plan view of a modified form of supporting slab, wherein reservoirs for the dye and conduits conducting the dye to apertures approximately in the center of the supporting slab are supplied;

Fig. 7 is a cross-sectional view taken on the line 7—7 of Fig. 6;

Fig. 8 is a longitudinal view of an improved form of cotton wadding, used to transfer the colored liquid from the gutters in the supporting slab to the absorbent material wherein the color is to be absorbed so that the colored artistic design may be formed therein;

Fig. 9 is an end view of the improved form of cotton wadding shown in Fig. 8; and

Fig. 10 is a typical artistic design produced in accordance with my improved process, this de-

sign being shown applied to a square of absorbent material such as paper or fabric.

In practicing my invention, the absorbent material on which the design is to be impressed in colors, is laid on a supporting slab, various forms of which are shown in Figs. 1 to 4 and Fig. 6. These slabs, designated by the numeral 11 in the drawing, may have a great many of different forms, but they are generally provided with peripheral grooves or gutters 12. In the form shown in Fig. 6, such peripheral gutters are not incorporated on the supporting slab, but this slab is intended for use in forming designs wherein the color is allowed to radiate by osmotic action from the center of the absorbent material, the dyestuff being guided to the center of the absorbent material by means of the conduits 13 as shown in the figure.

I have found that the supporting slabs may be cast out of a plastic material such as plaster of Paris, or they may be formed of resinite materials. When utilizing plaster of Paris, for the material forming the slabs, I have found it desirable to coat the slab, after it has been cast, with a material such as beeswax which is resistant to the action of the organic liquids utilized in forming the colored design. If the slab is constructed of resinite material, such as Bakelite, Vinylite, or any other of the commercially available resinites, it is possible, of course, to make the supporting slabs lighter in weight, and to the extent that the resins are resistant to the action of dyestuffs, it is unnecessary to apply any protective coating material on the surfaces of the finished supporting slab.

As shown in Figs. 1 to 4 inclusive, the supporting slab is formed with certain raised portions or ribs and a number of channels or grooves. The arrangement of ribs and grooves is illustrated in the drawings, although, of course, these arrangements are only typical of a number of arrangements that might be utilized. As previously noted, the supporting slabs shown in Figs. 1 to 4 all include the peripheral groove 12 extending entirely around the slab at its outer edges. However, as shown in Fig. 1, there are included in the slab shown in this figure, a number of circularly extending grooves, the center of which is the center of the slab, these grooves being designated by the numeral 15. In the arrangement shown in Fig. 2 there are provided the four intersecting grooves 16, 17, 18, and 19, which provide a cross design somewhat similar in form to that of the national flag known as the Union Jack. In the design for the slab shown in this figure, also, there are provided a number of basins for color receptacles 21 extending outside of the cross design, in which receptacles colored solutions may be placed which colored solutions may, in turn, be absorbed by the absorbent material on which the design is to be impressed.

In the arrangement for the supporting slab shown in Fig. 3, in addition to the peripheral groove 11, there is provided the interior groove 22 extending in the form of a square toward the center of the supporting slab. In Fig. 4, the supporting slab is supplied with an interior Y-shaped groove, in addition to the peripheral groove 12. This Y-shaped groove is designated by the numeral 24.

In the form of slab shown in Fig. 6, there are provided the four reservoirs or receptacles for color or colored solutions, designated by the numerals 25. These each lead to separate apertures 26, at the center of the slab. As previously ex-

plained, the colored solution or dyestuff is conducted from the receptacles or reservoirs 25 to the apertures 26 by means of the conduits 13, which are positioned within the interior of the slab. By utilizing this type of supporting slab, any number of colors may be conveyed to apertures positioned adjacent the center of the slab from which the colored solution is absorbed by the absorbent material at approximately the center, the solution radiating toward the peripheral portions of the absorbent material and thus forming the colored design.

In each one of the grooves shown in the supporting slabs of Figs. 1 to 4 inclusive, there may be positioned a wick-like material such as a piece of cotton wadding, which is adapted to convey the colors from the grooves in the supporting slab to the absorbent material on which the color design is to be impressed.

Figs. 8 and 9 show a typical piece of cotton wadding, of an improved form, which may be utilized in the grooves of the supporting slabs to practice my process. As shown, there is sewn to an ordinary piece of absorbent cotton 30, a piece of cotton bias tape 31, the two being held together by the three lines of stitching 33. In this way an absorbent cotton wicking strip is produced which has a superior life and will not sag down and lose its resiliency to an undue extent during use.

Fig. 1 illustrates my process wherein the colored design is to be impressed on a square piece of porous material, such as fabric or blotting paper designated by the numeral 35 while the strip of absorbent material is shown to be formed in the shape of a square, it could, of course, be shaped in any other form. Thus, it might be a rectangle, circle, ellipse, or it might have an entirely irregular shape. Of course, depending on the size of the supporting slab 11 on which it is laid, the material to which the design is to be imparted could be of any desired size.

In preparing the design on the absorbent material 35 in Fig. 1, I have selected to illustrate my process that illustrative form in which the design is applied by means of the peripherally arranged cotton wadding or other wick-like material 31, which is laid or positioned in the peripheral groove 12. Of course, the cotton wadding could be applied or positioned in the circular grooves 15, or it could be applied or positioned in the intersecting grooves of Fig. 2, or the interior grooves 22 of Fig. 3, or in the Y-shaped grooves 24 of Fig. 4. However, for purposes of illustrating my invention, I may show the process as practiced by positioning the wadding or wick-like material in the peripheral groove 12 of the slab 11 of Fig. 1. Of course, the principles on which my invention operate, apply equally well regardless of whether the color is applied peripherally to the absorbent material, as Fig. 1 illustrates, or whether it is applied to any other portion of the absorbent material such as would be accomplished, for example, by positioning the cotton wadding in the intersecting grooves 16, 17, 18 and 19 of Fig. 2.

There is first laid in the peripheral groove 12 of the slab shown in Fig. 1, the strips of cotton wadding 31, which may be ordinary cotton wadding, or which may be the reinforced cotton wadding of Figs. 8 and 9. I have secured good results with absorbent materials of other types, such as with kapok. However, some types of absorbent material, or wick-like material, such as substances derived from animals, such as felt, are

adversely affected by the dyestuffs utilized and cannot be employed at all successfully.

After the cotton wadding 37 is positioned in the peripheral grooves 12, or in any of the other grooves in which it is desired that it be positioned, it is then wet with the colored solution. This may be poured directly into the channel or grooves 12, and since the cotton wadding or other wick-like material utilized is absorbent, it will soak up the dyestuff. The absorbent material on which the design is to be impressed, 35, is then laid over the supporting slab in contact with the slab and with the cotton wadding 37 which is wet with the colored solution to be applied to the absorbent material 35. As shown, light pressing material, such as pieces of bent glass tubing, designated in the drawing by the numeral 39, may be laid on top of the paper or other absorbent material 35 so as to hold it lightly but securely in contact with the supporting slab 11.

Due to the absorbent character of the material 35, the color is absorbed from the cotton wadding 37 and travels by capillary action toward the center of the strip of absorbent material 35 on which the design is being formed. This piece of material may be allowed to remain in contact with the supporting slab and cotton wadding for any desired length of time, whereupon it is removed and allowed to dry. In the meantime, the slab and cotton wadding or other wick-like material 37 may be used to apply color to additional pieces of absorbent material 35 on which the design is to be formed. Then the cotton wadding 37 is removed, the supporting slab cleaned, and the process repeated using any other additional coloring dyestuff or solution of metal salts desired. The absorbent material 35 which has been previously coated with one color may thus be treated to apply another color thereto, or, in place of a second color, the second solution may be a solution of a metal salt as silver nitrate, gold chloride, gold bromide, etc. In this way, any number of different colors may be applied to the piece of absorbent material on which the artistic effect is desired. When utilizing the metal salt, particularly metal salt such as the silver and gold salt which darken or change color on exposure to light, it may be desirable to apply a light above the piece of absorbent material 35, as the metal salts are traveling into this absorbent material from the wadding 37 by capillary action, thus securing an infinite variety of shading and light and dark color as the process progresses. The resulting product from such a process wherein a solution of a metal salt which changes color on exposure to light is applied as the second or successive phase, following the application of a color to the absorbent material, is illustrated in Fig. 10. In this particular case, the first dyestuff applied to the strip or piece of absorbent material 35, peripherally as shown in Fig. 1, was a purplish red dye obtained by extracting pokeberry. This was followed, in a second treatment, by applying peripherally, by means of the wadding strips 37, a solution of silver nitrate, at the same time suspending a light above the surface of the material on which the artistic design was being impressed. While the figures indicate the complex variety of shades and colors produced by this two-color application, or rather by the application of color, followed by the application of a solution of a silver salt, the drawing, cannot, of course, do full justice to the beauty of the resulting design.

As previously pointed out, it is possible to obtain very similar designs on a second piece of absorbent material, or base material for the design 35, by repetition of the process. However, no two are exactly alike and the slight modification and variations in successive designs greatly enhance the artistic qualities of the resulting product.

It will be apparent, of course, that any number of colors, or any number of metallic salt solutions, or any number of other desired coloring agents, or any other suitable chemical agent for any purpose may be applied by means of the cotton wadding strips or wick-like elements 37 to the material 35, in which they will move laterally by capillary action to produce the desired artistic effect. Moreover, it will be apparent, that variations in the artistic effect can be secured by placing cotton wadding, either additional to that in the peripheral grooves 12, or without having wadding in the peripheral grooves 12, by placing the cotton wadding, for example, in the intersecting grooves 16, 17, 18 and 19 of Fig. 2, or in the Y-shaped grooves 24 of Fig. 4. Moreover, it will be clear, that most any arrangement of grooves may be provided in the supporting slab 11, and by positioning wick-like cotton wadding in the grooves or in certain selected ones of these grooves, it is possible, by the use of a sufficient number of colored solutions, or solutions of metallic salt, to obtain an almost endless variety of designs.

While I have described my process as utilizing successively two solutions or colored dyestuff, the piece of material 35, being allowed to dry after the application of the first color thereto, it will be, of course, evident that three, four or more colored solutions may be applied to the absorbent material 35 and that they may be employed by the peripherally, as illustrated in Fig. 1, or in any other way by laying the wick-like material which serves to convey the colored solution from the grooves to the absorbent material in any of the selected grooves or channels of the supporting slabs illustrated. Moreover, by utilizing the slab shown in Fig. 2, it is possible to provide or position the dyestuff in the small reservoirs or receptacles 21 of Fig. 2, and in this way secure peripheral application of the colored solution with the exception, however, that the color is applied interruptedly and not continuously around the periphery.

In practicing my process, utilizing the supporting slab shown in Fig. 6, the color is applied at the center of the absorbent material 35 which is positioned on the supporting slab, and allowed to move by capillary action radially toward the outer edges of the absorbent material. As shown, this is accomplished by placing the dyestuff or metallic solution utilized in the reservoirs 25, it being possible to place simultaneously or successively, as desired, a different colored solution, metallic salt, or other chemicals in each of these receptacles or reservoirs. It flows from these reservoirs, via the channels 13, to the apertures 26 in approximately the center of the slab, from which the color solution is soaked up or absorbed by the absorbent material 35 laid thereon. If desired, a piece of cotton wicking or wadding 70 may be positioned in the holes or apertures 26, to assist in the transference of color to the absorbent material 35, but this is not absolutely necessary. When utilizing metallic solution which changes color when exposed to light, as for example salts of silver and gold, it is pos-

sible, as when utilizing any other of these slabs for supporting the absorbent material 35, to position a light over the slab shown in Fig. 6, thus insuring the appearance in the design of a multitude of minute shadings having a very high artistic quality.

It is not essential that by specifying each of the various dyes or metallic solutions that I have utilized with success in producing artistic designs, both in single color and multicolor applications, as most any of the commercially available dyestuffs may be employed with success. For example, thiosalvine (a commercially-available dye-stuff containing sulfur), either in alcohol or other medium, may be utilized with complete success. I have specified above some of the various metallic salts with which I have secured very satisfactory results in solutions but I have not specified in full the natural material from which dyestuffs may be extracted, as their number is legion and I have obtained satisfactory results with a great many of them. My process may be utilized with any color solution, dyestuff, metallic salt, or modifying chemical such as formic acid, acetic acid, tannic acid, etc., and the particular colored solution utilized forms no important part of my process.

Restraining pressure devices 37 are provided on the paper to prevent the action of waves occurring over the area where the liquid is being absorbed. These waves or bulges result due to the expansion of the moistened area within a dry area. The device may be formed of glass rods or the like which are not affected by the liquid being used.

Various changes and modifications may be made in my improved process, which has been described as applied in connection with certain types of equipment illustrated herein, without departing from the spirit or scope of my invention. Some modifications and variations possible with the colored solution, wicking, absorbent material and construction and form of the supporting slab, have been referred to above in connection with the description of my process. However, various other changes and modifications may be made without departing from my invention, and it is my intention that these changes

and variations, to the extent that they are within the scope of the appended claim.

I claim:

The process of producing artistic colored designs on absorbent material which comprises, positioning a plurality of strips of absorbent wicking on a support, said strips being positioned thereon with respect to each other, in accordance with the arrangement of colored areas which is to comprise said colored design to be produced on said absorbent material, wetting said strips of wicking with a color producing solution, positioning the absorbent material on which the colored design is to be impressed on said support, said absorbent material being in contact with said wet wicking, allowing said absorbent material to remain in contact with said wicking until said color producing solution has moved throughout said absorbent material by capillary action, from said wicking, drying said absorbent material, repeating said sequence of operations utilizing as the color producing solution an aqueous solution of a metal salt which changes color when exposed to light, and subjecting said absorbent material to illumination during said latter part of said process wherein said absorbent material is in contact with wicking wet with said aqueous solution of a metal salt.
